(57) CLAIM

The ornamental design for outerwear as shown and described.

DESCRIPTION

FIG. 1 is a right side front perspective view of outerwear showing my new design;

FIG. 2 is a front view thereof;

FIG. 3 is a left side front perspective view thereof;

FIG. 4 is a left side view thereof;

FIG. 5 is a right side view thereof;

FIG. 6 is a rear view thereof; and,

FIG. 7 is a left side rear perspective view thereof.

The uneven-length broken lines depict portions of the outerwear that form no part of the claimed design.
